(57) **CLAIM**

I claim the ornamental design for a vapor product packaging, as shown and described.

DESCRIPTION

FIG. 1 is a top, front, right perspective view of a first embodiment of the claimed design in a first configuration; FIG. 2 is a bottom, front, right perspective view thereof; FIG. 3 is a front elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a rear elevation view thereof; FIG. 9 is a top, front, right perspective view of a second embodiment of the claimed design in the first configuration; FIG. 10 is a bottom, front, right perspective view thereof; FIG. 11 is a front elevation view thereof; FIG. 12 is a right side elevation view thereof; FIG. 13 is a left side elevation view thereof; FIG. 14 is a top plan view thereof; FIG. 15 is a bottom plan view thereof; and, FIG. 16 is a rear elevation view thereof. The broken lines in the drawings are for illustrative purposes only and form no part of the claimed design. Broken lines formed by equal length dashes show unclaimed subject matter. Broken lines formed by unequal length dashes (i.e., dash-dot) define bounds of the claimed design.
